OPEN HEARTH CHARGING DEVICE

William H. Mursch, Crafton, Pa., assignor to
 Carnegie-Illinois Steel Corporation, a corpora-
 tion of New Jersey

Application April 27, 1942, Serial No. 440,701

6 Claims. (Cl. 214—26)

The present invention relates to specific structural features of design and construction of open hearth charging machines and particularly to improved means for coupling a charging machine peel to a charging box.

Heretofore charging boxes for open hearth furnaces have usually included an open topped box with a socket formed at the end into which the extremity of the peel of the charging machine is lowered and locked in place so that the box can be raised from a car, moved into an open hearth furnace and inverted to empty its contents.

Conventional charging boxes, as made prior to my invention, have inherent defects. For example, prior art charging boxes have been so constructed that the material was apt to fall into the socket and interfere with proper coupling of the box with the peel. Moreover, in prior constructions the charging machine peel must be very accurately spotted before it can be lowered into the socket and it must be stopped at exactly the correct location in order to permit the entry of the usual locking pin, which must be properly positioned before the charging box can be lifted. If the peel is not stopped at the correct point in its downward stroke, either the peel or the socket of the charging box is very apt to be broken due to the peel striking the bottom of the socket. The same difficulty can be expected with the prior art construction when the box is being returned to the buggy after it is emptied in the event the peel is not brought to rest at the instant the box touches the top of the buggy. In prior art constructions the bearing surfaces must necessarily be very small, thus causing an undue amount of wear on the peel and the locking pin. The prior constructions are also objectionable in that the locking pin normally carries the full weight of the charging box and its contents while it is being lifted into the furnace.

The present invention aims to overcome the above and other inherent defects in the prior art charging machine apparatus. An outstanding characteristic of the present invention is that coupling means are provided which are so designed that instead of lowering the peel into a socket it is raised up for interengagement with cross bars incorporated in the end structure of the box.

A further feature is that the rear wall of the box is provided with a shield extension overlying the parts which detachably connect the charging box with the peel, thus preventing pieces of ma-

terial from dropping onto the cross bars which would interfere with the operation of coupling the peel of the charging machine with the box.

The above and other features of the invention will be fully apparent from the following detailed disclosure when read in connection with the accompanying drawings.

In the drawings:

Figure 1 is a plan view of a charging box embodying certain features of the present invention;

Figure 2 is a longitudinal section on line II—II of Figure 1;

Figure 3 is a transverse section on line III—III of Figure 2;

Figure 4 is a rear elevation of the charging box as viewed from the right of Figures 1 and 2;

Figure 5 is a view illustrating the relative position of a charging box and a coupling head on the extremity of a charging machine peel just prior to the time the two are about to be engaged;

Figure 6 is a view similar to Figure 5 but illustrating the relative positions of the parts after the coupling head of the peel has been operatively engaged with the charging box;

Figure 7 is a small scale cross sectional view of a charging machine showing the charging box in the position it occupies after it has been lifted from the scrap buggy and is about to be entered into the open hearth furnace; and

Figure 8 is a view similar to Figure 7 showing the parts after the peel has projected the charging box into the furnace and inverted it so as to discharge the contents thereof.

Referring in detail to the drawings, the numeral 10 represents somewhat conventionally a known form of open hearth furnace charging machine which is adapted to traverse tracks 12 which extend in front of a battery of open hearth furnaces, one of which is indicated at 14. Paralleling the furnace there is a narrow gauge track 16 along which travels a scrap car or buggy 18 which supports a plurality of charging boxes 20. The charging machine 10 is equipped with a conventional form of peel 22, the construction of which is well known to those skilled in the art. This peel is driven by power mechanism indicated diagrammatically at 24 mounted on the charging machine. The peel, as is well known to those skilled in the art, is capable of having a long stroke imparted thereto and is arranged to be lowered or lifted so as to periodically pick up charging boxes filled with scrap from the car 18 and to project them into the furnace where they are inverted, as suggested in Figure 8.

The present invention is directed to specific features of design and construction of the charging box and to the means for detachably coupling it to the extremity of the peel. The charging box is preferably constructed of flat rolled steel plate sections welded to one another. For example, it may include a rolled steel bottom plate 26 having transverse stiffening ribs 28 pressed upwardly therefrom. A front wall 30 having a transverse top reinforcing bead 32 is welded to the bottom plate 26, as shown at 34. Side walls 36 and 38 provided with upper reinforcing beads 40 and 42 may take the form of integral upward extensions of the bottom wall 26, as shown in Figure 3.

The rear wall 44 of the box is offset inwardly from the rear extremities 46 of the side walls, thus providing an open ended rear compartment 48 which is adapted to accommodate the coupler head indicated as a whole at 50, which is secured to a flange 52 carried by the outer extremity of the peel 22. The coupler head may be a separate piece, as shown, or it may be integrally secured to the peel, as will be obvious to those skilled in the art.

An upper cross bar 54 extends transversely from the side walls 36 and 38, thus bridging the upper portion of the chamber 48. A similar cross bar 56 is located below and slightly forward of the bar 54 and also bridges the space between the side walls 36 and 38. The upper extremity of the rear wall 44 is bent over into a substantially horizontal plane and extended rearwardly so as to form a shield 58 which overlaps a portion of the upper cross bar 54. As thus constructed and arranged the shield extension 58 is effective to prevent foreign matter, such as particles of scrap or ore, from dropping onto the cross bars, which particles would interfere with the proper coupling of the parts.

The coupling head 50 secured to the end of the peel includes respective upper and lower seats 60 and 62 and respective keeper lugs 64 and 66 adapted for interengagement with the upper and lower cross bars 54 and 56. The coupling head may be said to have respective seats and keeper lugs for detachable interlocking engagement with the cross bars which bridge the shielded chamber 48 at the rear extremity of the charging box. This chamber is of restricted width slightly greater than the transverse width of the coupling head. Thus the coupler head is prevented from moving laterally within the chamber by the side chamber boundary wall plates 49 and 51.

As above constructed and arranged, assuming the charging box is located on the scrap buggy 18, the peel 22 can be caused to move to the position approximately indicated in Figure 5 where the coupling head 50 is disposed in a plane which will permit the same to be freely moved toward the box below the cross bars 54 and 56. After the peel has been positioned at the elevation shown in Figure 5, the operator will actuate known types of control levers on the charging machine mechanism 24 so as to advance the peel toward the charging box and then cause it to elevate. Thus the interengagement between the coupling head 50 and the cross bars on the charging box shown in Figure 6 will be effected. Observation of Figure 6 will show that with the peel in the elevated position, the cross bars 54 and 56 engage the seats 60 and 62 and the keeper lugs 64 and 66 overlap the inner face of the cross bars. With the peel in this posi-

tion the operator actuates suitable known mechanism to advance a bar 68 longitudinally. This bar at its inner extremity carries a locking member 70 which is slideable in a guide passageway 72 formed in the coupler head 50. Figure 6 shows the locking member 70 advanced to position in which it overlaps the lower cross member 62. Thus the charging box is detachably interlocked with the coupler head 50 by reason of the joint action of the locking member 70 with the several keeper lugs and the upper and lower cross bars.

With the parts thus interlocked the peel can be operated so as to project the charging box into the interior of the open hearth furnace 14, for example to the position shown in Figure 8, whereupon the operator causes the peel 22 to rotate on its longitudinal axis to thus invert the box and dump the contents thereof into the furnace.

From the foregoing it is apparent that apparatus embodying the improved structural features of the present invention overcomes a number of the inherent defects in the prior art devices hereinbefore referred to. For example, the shield extension 58 on the rear wall of my improved charging box serves to prevent pieces of material from dropping onto the cross bars where they would interfere with the peel of the charging machine. The improved apparatus is also so constructed and arranged that it need not be stopped during its forward and upward motion when engaging the box in order to seat the locking member since the machine is so arranged as to permit operation of this member while the peel is in motion. The same applies to the unlocking operation when the box is being returned to the buggy 18.

In the improved apparatus the locking member 70 carries the weight of the charging box only when the latter is in inverted position in the furnace while emptying the load. At other times, for example when the box is filled with scrap, the locking member is relieved of the entire load, this load being taken wholly by the coupling head 50 and heavy cross bars 54 and 56 due to the interconnection between the seats and keeper lugs thereof with the cross bars.

My improved charging box need not be stopped accurately on the down stroke when returning the box to the buggy 20 because the locking pin is withdrawn while the box is in motion and the sloping surface of the peel will merely slide the box on the buggy after the peel is still further lowered without racking it out. A skillful charging machine operator will be able to pick up the box of the present invention and move it either into or out of the furnace with a sweeping motion and thus save considerable time in handling the charging boxes.

Since the locking member in my novel apparatus is relieved of the weight of the loaded boxes, its useful life will be increased as compared to prior art constructions. A further advantage of the improved construction is that larger bearing surfaces are provided. This will eliminate the causes for overstraining of the box socket and the peel ends, thus the life of these parts will be greatly increased.

From the foregoing it is manifest that the improved apparatus shown and described differs structurally from conventional apparatus heretofore used for a similar purpose, and that because of these differences in structure, impor-

tant operating and maintenance economies are secured.

While I have described quite precisely a preferred embodiment of the invention, it is not to be construed that I am limited thereto since various modifications and substitutions of equivalents may be made by those skilled in the art within the scope of the appended claims.

I claim:

1. An open hearth furnace charging machine including a peel adapted to be moved into and out of the furnace, a charging box having a novel detachable coupling with the peel comprising a pair of cross bars at one end of the box, and a hook-like head located at an extremity of the peel having respective seats and keeper lugs projecting upwardly therefrom adapted to be moved upwardly to detachably engage said cross bars.

2. An open hearth furnace charging machine including a peel adapted to be moved into and out of the furnace, a charging box having a novel detachable coupling with the peel comprising a pair of spaced cross bars at one end of the box, a hook-like coupler head located at an extremity of the peel having respective seats and keeper lugs projecting upwardly therefrom adapted to be moved upwardly to detachably engage said cross bars, and a shield projecting outwardly from one end of the box over the top of the extremity of said coupler head and effective to exclude foreign matter which would tend to interfere with the interengagement of said keeper lugs and said cross bars.

3. An open hearth furnace charging machine including a peel adapted to be moved into and out of the furnace, a charging box comprising a bottom wall, side walls, a front wall and a back wall, portions of the side walls being extended beyond the back wall thus forming an open ended chamber at the rear of the box, spaced cross bars located in said chamber and extending from side wall to side wall, the back wall having an upper rearwardly extended shield portion engaging one of said cross bars, and a coupler head secured to the extremity of the peel and having respective seat portions and keeper lugs for detachable engagement with said cross bars.

4. An open hearth furnace charging machine including a peel adapted to be moved into and out of the furnace, a charging box comprising a bottom wall, side walls, a front wall and a back wall, portions of the side walls being extended beyond the back wall thus forming an open ended

chamber at the rear of the box, spaced cross bars located in said chamber and extending from side wall to side wall, the back wall having an upper rearwardly extended shield portion engaging one of said cross bars, a hook-like coupler head secured to the extremity of the peel and having respective seat portions and keeper lugs for detachable engagement with said cross bars, a locking member movable longitudinally of the peel adapted to coact with one of said cross bars, and a guideway in said coupler head with which said locking member slidably coacts.

5. An open hearth furnace charging machine including a peel adapted to be moved into and out of the furnace, a charging box comprising a rolled steel bottom plate, rolled steel side wall plates welded thereto along their lower edges, a rolled steel front wall welded to the bottom plate and to the side plates, a back wall plate welded to the bottom plate at a location inward from the rear end of the side walls to thus define an open ended chamber, upper and lower cross bars bridging said chamber and secured at their respective ends to said side plates, said back wall having an upper rearwardly extended shield portion engaging the upper cross bar, and a duplex hook-like coupler head secured to the extremity of the peel having respective upper and lower seats and respective upper and lower keeper lugs for engagement with said upper and lower cross bars.

6. An open hearth furnace charging machine including a peel adapted to be moved into and out of the furnace, a charging box comprising a rolled steel bottom plate, rolled steel side wall plates welded thereto along their lower edges, a rolled steel front wall welded to the bottom plate and to the side plates, a back wall plate welded to the bottom plate at a location inward from the rear end of the side walls to thus define an open ended chamber, upper and lower cross bars bridging said chamber and secured at their respective ends to said side plates, said back wall having an upper rearwardly extended shield portion engaging the upper cross bar, a duplex hook-like coupler head secured to the extremity of the peel having respective upper and lower seats and respective upper and lower keeper lugs for engagement with said upper and lower cross bars, and a locking member movable longitudinally of the peel, said coupler head having a guideway formed therein for coaction with the locking member.

WILLIAM H. MURSCH.
